UNITED STATES PATENT OFFICE.

JOHN C. BOSS, OF ELKHART, INDIANA.

APPARATUS FOR DRYING BRICK AND OTHER CLAY ARTICLES.

Application filed December 3, 1921. Serial No. 519,628.

To all whom it may concern:

Be it known that I, JOHN C. BOSS, a citizen of the United States, and resident of Elkhart, in the county of Elkhart and State of Indiana, have invented certain new and useful Improvements in Apparatus for Drying Brick and Other Clay Articles, of which the following is a specification.

My present invention relates to improvements in apparatus for drying clay products and is designed more especially for clay articles being shown herein as embodied in apparatus designed more especially for drying brick.

The invention aims to provide an apparatus by which such articles may be uniformly and thoroughly dried in large quantities in a very short period of time and at a great saving in cost.

With these and other objects in view the invention includes the novel features of construction and arrangement and combination of parts hereinafter described and particularly defined by the appended claims.

An embodiment of my invention is illustrated in the accompanying drawings in which—

Figure 1 is a plan view with parts broken away, showing my invention as embodied in a four tunnel brick drying plant.

Fig. 2 is a detail view broken away to show the tunnel floor.

Fig. 3 is a transverse vertical section on line 3—3 of Fig. 1 on a larger scale.

Fig. 4 is a longitudinal vertical section on line 4—4 of Fig. 1.

Referring by reference characters to these drawings, my improved apparatus comprises a drying building or structure of suitable material embodying roofed parallel exterior walls 2, and intervening walls 2^a providing a plurality of drying tunnels or chambers designated 3, four of which are shown as a convenient number, although it will be understood that any number of tunnels desired may be used, corresponding to the desired capacity of the plant.

The walls of the tunnels are preferably constructed of brick or like material and they are closed at the top as by the roof 1, extending the entire length of the tunnels.

Above this is a second and parallel roof 1^a providing an intervening space which is di-

vided by partitions 1^b to form a plurality of flues 1^x, one located centrally over each tunnel with which it communicates by air passage openings *a* beneath which are preferably located baffle plates *a'*. The tunnels are made of sufficient length (say 100 feet) to receive an adequate number of cars loaded with brick or other clay articles.

These cars which are designated 5, may be of the ordinary or any desired construction, and are designed to be run into and through the tunnels upon tracks 6 provided for this purpose. The tunnels are provided at opposite ends with closures or doors 7 which are designed to be opened to admit the cars and closed to confine the heated air to the tunnels during the drying operation.

The bricks or other articles to be dried are piled upon the platforms in spaced arrangement, as shown, so as to permit the drying air to pass freely between and around the same, the platforms themselves having openings to permit the passage therethrough.

In using tunnels for drying clay articles, such as brick for example, I have found that if the tunnels are made long enough to give a reasonably large capacity to the plant, great difficulty is encountered in securing a rapid, uniform and complete drying, due to the formation of pockets or places of non-circulation of air. This is avoided by my present apparatus in which I use a down draft of the air through or between the brick, supplying the heated air to and distributing it uniformly throughout the space above the cars under pressure, and exhausting it uniformly from all portions of the spaces beneath the cars by suction.

The necessary heated air supply may be secured from the waste heat of the kilns conducted through a waste heat flue 9, which communicates fan chamber 9^a and flue 9^b with chamber or flue 9^c located preferably over approximately the longitudinal center of the tunnels and having its open bottom in communication with the flues 1^x. An air forcing device, such as a fan of any suitable design, is located in a convenient position, as in fan chamber indicated at 9^a, and serves to supply the air under the requisite pressure to force it to all parts of the supply flues 1^x.

Located transversely beneath the tunnels, and preferably adjacent to the fan casing

9^a is an exhaust flue 10 in which suction is produced by suitable means, such as a suction fan, indicated conventionally at 11.

Beneath the tunnels are located air supply 5 mains or underground conduits 13, preferably one centrally beneath each tunnel, which run the entire length of the tunnels, being closed at their outer ends and connected at their inner ends to the common 10 main air exhaust duct or flue 10.

The flues are preferably of tapered form, as shown in Fig. 3, and are provided with 15 openings 13^a at suitable intervals communicating with the interior of the tunnels, beneath which openings are provided baffle plates 13^b.

By this arrangement it will be seen that the heated or drying air is introduced centrally into the supply conduits under pressure and is thence forced in opposite directions into the flues 1^a, from which it passes at equidistantly spaced points into the tunnels throughout the entire length thereof. It is thus caused to flow over the tops 25 of the bricks or other articles so as to be distributed evenly over the entire surface of the loads on each car.

The suction flues through the passages 13^a serve to remove the moisture laden air and 30 insure the passage of the air through the brick from the top downwardly through the platform openings without having any travel of the air longitudinally through the tunnels.

35 In carrying out my invention, I prefer to use trucks or truck platforms which are adapted to abut each other, end to end, and it will be readily seen that the air, brought into the conduits under pressure, is supplied 40 to the tops of the tunnels at equidistant points throughout the entire lengths thereof. As the only escape for the air is by way of the outlets between the rails and the only way of reaching these outlets is 45 through the spaces between the articles, and openings in the car platforms, and as the space beneath the cars is under strong suction, said articles are quickly and thoroughly dried by reason of the heated air under pressure 50 passing downwardly around and between all the articles of each car or truck platform which is subjected continuously to individual currents of fresh drying air, the moisture laden air being withdrawn under 55 strong suction applied at equidistantly spaced points throughout the length of each tunnel.

While I have shown in the drawings the

air supply and exhaust conduits as connected with the tunnel flues approximately midway of the length of the tunnels, it will be understood that this is my preferred embodiment of the invention.

Having thus described my invention, what I claim is:

1. Apparatus for drying brick and other clay products comprising a closed tunnel having means for permitting loaded cars to be passed into the same, a blower having connections for forcing air under pressure 70 into the upper part of said tunnel and a fan for exhausting the air from the bottom of the tunnel.

2. Apparatus for drying brick comprising a closed tunnel having means for permitting loaded cars to be passed thereinto, a blower having connections for introducing air under pressure into the upper portion of said tunnel at a plurality of points throughout the entire length of the tunnel and a 80 suction fan for exhausting the air from the bottom of said tunnel at a plurality of points.

3. Apparatus for drying brick and other clay products comprising a closed tunnel 85 having means for permitting loaded cars to be passed thereinto, air conduits above and below said tunnel, and communicating therewith, a blower for supplying air under pressure to the upper conduit and a suction fan 90 for exhausting air from the lower conduit.

4. Apparatus for drying brick and other clay products, comprising a closed tunnel having means for admitting loaded cars thereto, an air conduit communicating with the top of the tunnel, an air conduit communicating with the bottom of the tunnel, a blower for forcing air into one of said conduits, and a suction fan arranged to withdraw air from the other conduit.

5. Apparatus for drying brick and other clay products comprising a series of closed tunnels arranged side by side and having means for admitting loaded cars thereto, conduits above and beneath said tunnels, 105 and communicating therewith, a transverse flue located above the upper conduits and communicating therewith, a blower for supplying heated air under pressure to said transverse flue, a second transverse flue beneath the tunnels communicating with all of said lower conduits, and a suction fan for exhausting air from said second transverse flue.

In testimony whereof, I affix my signature. 115
JOHN C. BOSS.
